FOREIGN PATENT DOCUMENTS

EP 2449906 A2 5/2012

Primary Examiner — T. Chase Nelson(74) *Attorney, Agent, or Firm* — Thompson Patent Law;
Craige Thompson(57) **CLAIM**

The ornamental design for a shoe outsole, as shown and described.

DESCRIPTION

FIG. 1 is a front perspective view of a shoe outsole showing the new design;

FIG. 2 is a plan view of the shoe outsole of FIG. 1;

FIG. 3 is a rear perspective view of the shoe outsole of FIG. 1; FIG. 4 is an enlarged, partial view of encircled area 4 in FIG. 2; and,

FIG. 5 is an enlarged, partial side view of the shoe outsole of FIG. 4.

The broken lines shown in the drawings illustrate unclaimed portions of the shoe outsole and form no part of the claimed design.

1 Claim, 5 Drawing Sheets---
